UNITED STATES PATENT OFFICE.

MILTON CLEVENSTINE, OF KIMBERTON, PENNSYLVANIA.

WRENCH.

No. 875,048.

Specification of Letters Patent.

Patented Dec. 31, 1907.

Application filed March 30, 1907. Serial No. 365,558.

To all whom it may concern:

Be it known that I, MILTON CLEVENSTINE, a citizen of the United States, residing at Kimberton, in the county of Chester and State of Pennsylvania, have invented new and useful Improvements in Wrenches, of which the following is a specification.

This invention relates to wrenches and more particularly to ratchet wrenches, the object 10 being to provide a ratchet wrench which can be operated in either direction so as to screw up a nut or unscrew the same.

Another object of my invention is to provide very novel means for locking the pawls 15 out of engagement with the ratchet wheels.

Another object of my invention is to provide the ratchet wheels with an adjustable jaw so that they can be adjusted to suit different size nuts.

20 With these and other objects in view, the invention consists in the novel features of construction, combination and arrangement of parts hereinafter fully described and pointed out in the claims.

25 In the drawing forming a part of this specification: Figure 1 is a bottom plan view of my improved wrench. Fig. 2 is a side elevational view of the same. Fig. 3 is a section taken on lines 3—3 of Fig. 1. Fig. 30 4 is a detail sectional view showing the pawl.

In the drawing A indicates a handle provided with an offset arm A' at one end, having an aperture A² in its end, in which is 35 loosely mounted a machine bolt B, extending out centrally from a pair of oppositely toothed ratchet wheels C and D, which are secured together by machine-screws E.

Secured on the outer face of the wheel D 40 is a rectangular shaped jaw F, provided with apertured ears F', through which screws pass and securely lock the jaw on the wheels. The side walls of the frame are beveled in which is slidably mounted a wedge-shaped 45 jaw G, provided with a sleeve G' in which is swiveled the head of a thumb-screw H, which is mounted in a threaded boss F² in one end, of the frame, so as to adjust the jaw to suit different size nuts.

Spaced bores J and K are formed in the 50 end of the handle communicating with bayonet-slots J', K' formed on the top of the handle and with slots formed in the side of the handle. Coiled springs L are arranged in the bores which bear against the ends of 55 pawls M N slidably mounted in the bores having threaded openings adjacent their ends, in which are secured pins M', N' which extend out through the bayonet-slots and are provided with heads at their ends, so 60 that they can be readily operated in the slots with the finger. The ends of the pawls are oppositely beveled so as to fit in between the teeth and slide over the respective ratchet wheels. 65

It will be readily seen that either of the pawls can be drawn out of engagement with the respective ratchet-wheels, and locked so that the wrench can be used for turning a 70 nut in any direction desired.

Having thus fully described my invention, what I claim as new and desire to secure by Letters Patent is:—

1. In a wrench, the combination with a 75 handle, provided with an offset arm at one end, of a pair of oppositely toothed ratchet wheels secured together loosely mounted on the end of said arm, a jaw secured on the face of the outer ratchet wheel and spring actuated pawls mounted in the ends of the 80 handle carrying pins working in bayonet-slots formed in the handle.

2. The combination with a handle, provided with spaced bores at one end, communicating with bayonet-slots formed in the 85 handle, of an offset arm extending out from said end, oppositely toothed ratchet-wheels mounted on the end of the said arm, an adjustable jaw secured on the face of the outer ratchet wheel, spring actuated pawls mounted in said bores, and pins carried by said 90 pawls working in said bayonet-slots.

MILTON CLEVENSTINE.
